UNITED STATES PATENT OFFICE.

LUTHER F. SEELAR, OF ST. LOUIS, MISSOURI, ASSIGNOR TO ST. LOUIS CAR COMPANY, OF ST. LOUIS, MISSOURI, A CORPORATION OF MISSOURI.

PLATFORM SUPPORT FOR RAILWAY CARS.

Application filed August 11, 1923. Serial No. 656,771.

To all whom it may concern:

Be it known that I, LUTHER F. SEELAR, a citizen of the United States, residing at city of St. Louis and State of Missouri, 5 have invented certain new and useful Improvements in Platform Supports for Railway Cars, of which the following is a specification.

This invention relates to railway cars, and 10 more particularly to a side sill or sill extension for the platform at the end of a car.

The side sill extension on which the car platform is mounted is generally referred to as a "platform knee."

15 As the platforms are generally on a different plane from the car body floor, it is necessary to deflect this knee downwardly and as a rule inwardly at the same time. The usual method of constructing a platform knee for trolley cars is to employ a 20 large structural angle which is bent into the proper shape and reenforced at the bend by flat bars.

Another method of forming platform 25 knees is to employ a heavy structural channel of the type generally known as a ship channel, bended into shape, and reenforce the web of the channel with flat plates.

The necessity of bending the metal to the 30 desired shape and then reenforcing it calls for a large amount of labor in the construction of these articles.

In order to simplify the construction and 35 obtain the desired results with the minimum of labor and material, I form a cast steel knee of the desired shape in which the parts are proportioned to resist direct load and torsional strains. The knee is further constructed so that it increases in strength with 40 increase of stress, and the labor of fabrication and attachment to the car is reduced to a minimum.

In the accompanying drawings, I have 45 shown one embodiment of the invention.

45 In this showing:

Figure 1 is a diagrammatic illustration of the frame of a car body,

Figure 2 is a side elevation of the platform knee,

50 Figure 3 is a plan view thereof,

Figure 4 is a vertical sectional view on line 4—4 of Figure 2, and

Figure 5 is a similar view on line 5—5 of Figure 3.

55 Referring to the drawings, the reference

numeral 1 designates the side sills of a car body which are arranged over the truck and connected at intervals by transverse members 2. The end of the car body is rounded and is provided with an end sill 3 shaped to fit under the platform. As shown, the side sills terminate inwardly on the ends of the car and a platform knee or side sill extension 4 is arranged between the end sill and the side sills of the car. This knee is 60 formed of cast steel and is shaped to fit the car body to which it is attached. As shown, the inner end 5 extends at an angle to the body portion and is deflected upwardly, the floor of the car body being elevated above 65 the platform of the car. The outer end of the knee is provided with a flat face 6 for the attachment of the bumper. Adjacent the outer end, the knee is provided for the flat portion 7, adapted to form a support for 70 the crown of the trolley car. The upper face beyond this portion is substantially flat as at 75 8, and side walls 9 extend downwardly therefrom. The lower face 10 extends at an angle to the upper face, increasing the cross 80 sectional area of the knee toward the center at the point where the greatest strength is required. Adjacent the bend connecting the offset portion 5 to the main portion 4 of the knee, there is provided a transverse 85 web 11, furnishing a reenforcement. Rearwardly of this web, the sides are extended upwardly, as indicated at 12, above the top and these extensions continue to a point beyond the bend. The extensions are provided 90 with flattened upper portions 13, forming a substantially T-shaped cross section at the point of the bend, adapted to receive the adjacent transverse sill 2, arranged at the junction of the car body and 95 the platform. As shown, the web 11 extends slightly above the horizontal portions 13, forming a lip 14 against which the side of the sill rests. The inner end of the knee is provided with an extended flattened face 100 15 to which the side sill 1 of the car is secured.

The advantages of this device will be apparent to one skilled in the art. By providing a cast steel knee, the labor incident 105 to the construction of platform knees is reduced to a minimum. The knee may be cast the proper size for a given type of street car body with the rear end 5 deflecting the proper distance both horizontally and verti- 110

2
cally and readily placed in position by merely fastening the end sill to the extension 13 of the knee and the side sill to the flattened face 15 by means of bolts, rivets or the like. 5 The increase in the cross sectional area of the sill intermediate its ends provides the necessary support at the desired point to resist the increased stress and the web 11 and extensions 12 reenforce the knee at the 10 point of the bend, eliminating the necessity of attaching separate plates when the device is assembled.

It is to be understood that the form of the invention herewith shown and described 15 is to be taken as a preferred example of the same, and that various changes in the shape, size, and arrangement of parts may be resorted to without departing from the spirit of the invention or the scope of the 20 subjoined claims.

Having thus described my invention, I claim:

1. A cast knee for car platforms comprising a body portion having one end extending 25 at an angle thereto, and integral reinforcing means adjacent the junction of the body portion and said end.
2. A cast knee for car platforms comprising a body portion having one end extending 30 at an angle thereto, and integral reinforcing means adjacent the junction of the body portion and said end, the cross

sectional area of said body portion increasing toward the center thereof.

3. A cast knee for car platforms comprising a body portion having its outer end rounded to permit it to be secured to the bumper sill of the car, said body portion being extended at an angle at a point adjacent the center thereof, and integral reinforcing means formed on said body portion adjacent said angle. 35 40

4. A cast knee for car platforms comprising a body portion having a rounded outer end adapted to be secured to the bumper sill of a car and a flattened portion formed on the inner end adapted to be secured to the side sill, said body portion increasing in cross sectional area intermediate its ends. 45

5. A cast knee for car platforms comprising a body portion having one end arranged at an angle thereto, a transverse web formed on said body portion adjacent the junction of said end, and extensions formed on said body portion and extending longitudinally thereof at the junction of said body portion and end. 50 55

In testimony whereof, I affix my signature in the presence of two witnesses.

LUTHER F. SEELAR.
